(57) **CLAIM**

The ornamental design for a camera with fold-up display, as shown and described.

DESCRIPTION

FIG. 1 is a perspective view of a camera with fold-up display showing our new design in a fold-up position; FIG. 2 is a perspective view thereof, the camera being in an alternate position with the display open;

FIG. 3 is a front elevational view thereof;

FIG. 4 is a left side elevational view thereof;

FIG. 5 is a top plan view thereof;

FIG. 6 is a bottom plan view thereof;

FIG. 7 is a right side elevational view thereof; and,

FIG. 8 is a rear elevational view thereof.

The broken lines in FIG. 2 are shown to illustrate environment only and form no part of the claimed design.
